[57] ABSTRACT

A process is provided for removing metal contaminants such as vanadium, nickel and iron, particularly vanadium and nickel, from hydrocarbon fractions. The process comprises contacting the hydrocarbon with an extractant comprising molten sulfur and a Group VB metal salt.

20 Claims, No Drawings

PROCESS FOR REMOVING METALS FROM PETROLEUM RESIDUA

The present invention relates to the removal of metal contaminants from hydrocarbon fractions. More particularly, the present invention relates to a process for removing heavy metals such as vanadium, nickel or iron, particularly vanadium and nickel, from petroleum fractions such as crude oil or residual fractions.

Many hydrocarbon feedstocks contain appreciable amounts of heavy metals such as vanadium, nickel and iron or compounds thereof. These metallic contaminants may exist within the hydrocarbonaceous material in a variety of forms, generally being present as complexed organometallic compounds of relatively high molecular weight, for example as metal porphyrins and various derivatives thereof. These heavy metals or metal compounds can deteriorate the activity of and poison certain types of catalysts, when present in feedstocks subjected to catalytic treatment. Cracking catalysts, such as silica-alumina catalysts, alone or in admixture with other metal oxides suitable for cracking, are particularly susceptible to deterioration and poisoning by heavy metals such as vanadium, iron and nickel and the like.

The problems surrounding the presence of these heavy metal contaminants have long troubled those working in the art; however, efforts heretofore made to reduce the levels of such contaminants have not been entirely satisfactory. U.S. Pat. No. 2,854,399 states that petroleum fractions derived from crude oils, and containing heavy metal components deleterious to the cracking of such oils, can be catalytically cracked after contacting such fractions with sulfur and removing any resulting heavy metal sulfides and excess elemental sulfur. While this method does aid in reducing the levels of heavy metal contaminants, certain of the contaminants, especially vanadium, remain in sufficient amounts to rapidly poison the cracking catalysts. U.S. Pat. No. 3,474,029 relates to a process for hydrorefining a metal contaminated, asphaltene-containing hydrocarbon charge stock. According to this patent, the charge stock is contacted with a catalyst and hydrogen in the presence of a thioester of a metal selected from the group consisting of metals of Group VB and Group VIB to maintain the activity of the catalyst. U.S. Pat. No. 3,619,410 states that metallic contaminants can be removed during the conversion of hydrocarbonaceous black oils with hydrogen and hydrogen sulfide by the addition of an aqueous solution of the double salt vanadyl sulfite-ammonium sulfite. The approaches suggested by the latter two patents require the use of costly materials and are restricted to highly inflexible processing schemes.

It is an object of the present invention to provide a highly flexible and efficient method for removing metal contaminants such as vanadium, nickel and iron from hydrocarbon fractions.

This and other objects are accomplished by the present invention which provides a process for reducing the level of metal contaminants in a hydrocarbon material which comprises contacting the hydrocarbon with an extractant comprising elemental sulfur and a Group VB metal salt, and thereafter separating at least a portion of the extractant and metal contaminants from said hydrocarbon material.

While any hydrocarbon feedstock containing metal contaminants can be treated according to the process of the present invention, this process is particularly suitable for removing metal contaminants from petroleum materials such as crude oil or residual fractions, especially from long residua (a major portion of the fraction boils in excess of 460°F at atmospheric pressure) and short residua (a major portion of the fraction boils in excess of 1,000°F at atmospheric pressure). 5 The hydrocarbon materials may typically contain from about 100 to 3,000 wppm vanadium, 10 to 1,500 wppm nickel, and 10 to 1,500 wppm iron.

While the process of the present invention can effectively remove substantial amounts of most heavy metals, it is particularly suitable for the removal of such contaminants as vanadium, nickel and iron, particularly vanadium and nickel.

According to the present invention, the hydrocarbon material is contacted with an extractant comprising 10 molten elemental sulfur and a Group VB metal salt. Typical of the salts which can be used are sulfides, oxides, and selenides of vanadium, niobium and tantalum. Vanadium sulfides, especially vanadium sesquesulfide (V₂S₃) and vanadium pentasulfide (V₂S₅) or mixtures 15 thereof, are particularly preferred. The Group VB metal salt can be either supported or unsupported. When unsupported it can be added before or after admixture of the hydrocarbon with the sulfur. When supported, the Group VB metal salt is typically dispersed 20 on a support material such as silica, alumina, silica-alumina, titania, zirconia, thoria, and the like, and the hydrocarbon and molten sulfur are mixed and passed 25 thereover. Whether the Group VB metal salt is supported or unsupported, the sulfur is used in an amount 30 of from about 0.001 to 10 wt. percent based on the weight of the hydrocarbon, preferably 0.5 to 5.0 wt. percent, and most preferably 0.9 to 1.5 wt. percent. The Group VB metal salt functions as a promoter, and, 35 whether supported or unsupported, it must be used in an effective promoting amount. When unsupported, the Group VB metal salt is preferably present in amounts ranging from 0.1 to 10 wt. percent, most preferably 0.5 to 2.0 wt. percent, based on the weight of the hydrocarbon feed. When supported, the hydrocarbon/sulfur mixture is passed over the supported Group VB 40 metal salt at a space velocity within the range of from about 0.01 to 100, preferably 1 to 5, volumes of oil and sulfur per volume of supported Group VB metal salt 45 per hour (v/v/hr.).

50 The treatment temperature employed according to the present invention must be sufficiently high in order to provide liquid phase contact; however, the treatment temperature should be below about 400°C. Above this temperature substantial reaction of the sulfur with the hydrocarbon is experienced and undesirable sulfur compounds are produced. Typically, the treatment temperature ranges from about 150° to 350°C, and preferably from about 200° to 300°C. The reaction 55 zone pressure is not critical. The contacting period may range from about 0.1 to 10 hours, preferably from about 0.2 to 2 hours.

60 The sulfur/Group VB metal salt extractant and the hydrocarbon feed are preferably contacted in a mixing zone provided with a mixing apparatus capable of causing intimate contact between the phases. Centrifugal pumps, mixing orifices, paddle wheels, and other high shear devices, or combinations thereof, are suitable 65

means for assuring intimate contact between the sulfur/Group VB metal salt extractant and the hydrocarbon being treated.

Following contact of the hydrocarbon with the sulfur/Group VB metal salt extractant, the extractant containing the metal contaminants (i.e., contaminant metals that are complexed and/or compounded with the sulfur, the Group VB metal salts, and any unreacted sulfur) are removed from the treated oil. These materials may be removed immediately following the contacting step or after subsequent processing steps where such subsequent steps will not result in adverse reactions with, or be retarded by, the presence of these materials. These materials are preferably removed from the oil by dissolving the oil therefrom with a hydrocarbon solvent at a temperature within the range of from about 20° to 100°F and at a pressure within the range of from about atmospheric pressure to 500 psig. The particular solvent employed is not critical but can be any effective material from propane up to a refinery naphtha stream. Preferred solvents include paraffinic hydrocarbons or mixtures thereof, with heptane being particularly preferred. Typically, from 2 to 10, preferably 3 to 5, volumes of solvent are employed per volume of oil.

Alternatively, separation can be accomplished by simply permitting the oil/sulfur mixture to stand for a period of time sufficient for the unreacted sulfur, the Group VB metal salt, and the reacted and/or complexed contaminant metals, to settle out from the hydrocarbon material. Substantially complete separation by settling will occur within about 8 hours. The settling period can be markedly reduced by centrifuging the total mixture.

The following examples are presented for the purpose of more clearly illustrating the present invention and are not to be taken as limiting the invention to the particular reactants or conditions employed.

EXAMPLES 1-9

In each of the following examples, the designated amount of 460°F+ residual cut from Venezuelan crude was contacted with the specified extractant in a pyrex tube that was positioned within an oil bath maintained at the indicated temperature. This residua contained 290 wppm vanadium, 37 wppm nickel, 2.23 wt. percent sulfur, and exhibited a gravity of 16.9° API and a Conradson carbon number of 10.7 percent. In each example, the extractant and the residua were continuously agitated by bubbling nitrogen through the tube. After allowing the residua and extractant to react for one hour at atmospheric pressure, the tube was removed from the bath and the contents cooled. Thereafter, the treated oil was contacted and stirred with 200 milliliters of normal heptane at room temperature for about 1 hour. The total mixture was then centrifuged to remove the solids. The resulting solids were thereafter washed with additional heptane to remove residual oil and then dried in air at room temperature. Both the recovered oil and the solid materials were analyzed using emission spectroscopy techniques. The vanadium sesquesulfide (V_2S_3) used in these examples was prepared by treating vanadium pentoxide (V_2O_5) with hydrogen sulfide (H_2S); about 50 percent of unreacted vanadium pentoxide still remained in the samples used. Unless otherwise stated, all parts and percentages are by weight. Table I summarizes the results obtained.

Example 1 is a control experiment and indicates the degree of metals removal which can be achieved according to the processing scheme employed without the addition of an extractant. Examples 2 and 3 illustrate the highly efficient metals removal which can be achieved by using the extractant according to the present invention. As noted above, the vanadium sulfide used was, in fact, a mixture of V₂S₃ and V₂O₅ as added to the reaction zone. A comparison of Examples 2 and 3 with Example 7 shows, however, that a substantial difference in performance is secured when one starts with a mixture containing at least some vanadium sulfide as opposed to starting with vanadium pentoxide. Additionally, a comparison of the results of Examples 2 and 3 to the results of Examples 4 and 5 indicates a clear superiority of the use of the extractant of the present invention as opposed to the use of sulfur alone. And, comparative Example 6 illustrates that other materials such as sodium sulfide do not function in the same manner as the vanadium material.

Comparison of Examples 2, 8 and 9 shows a definite synergism in the use of mixtures of V₂S₃ with sulfur rather than the use of either component alone.

What is claimed is:

1. A process for reducing the level of metal contaminants in a hydrocarbon material selected from the group consisting of crude oil or a residual petroleum fraction which comprises contacting the hydrocarbon material at a temperature below 400°C. with an extractant comprising 0.001 to 10 wt. percent, based on the weight of the hydrocarbon, of elemental sulfur and a promoter selected from the group consisting of supported and unsupported oxides, sulfides, and selenides of vanadium, tantalum, niobium or mixtures thereof, and in the case where the promoter is unsupported the promoter is present in an amount of from 0.1 to 10 wt. percent, based on the weight of the hydrocarbon, and thereafter separating at least a portion of the extractant and metal contaminants from said hydrocarbon material.

2. A process according to claim 1 wherein the hydrocarbon is contacted with the extractant at a temperature of from about 150° to 350°C.

3. A process according to claim 1 wherein the sulfur is present in an amount of 0.5 to 5.0 wt. percent based on the weight of the hydrocarbon.

4. A process according to claim 3 wherein the sulfur is present in an amount of from 0.9 to 1.5 wt. percent based on the weight of the hydrocarbon.

5. A process according to claim 1 wherein the promoter is unsupported and is present in an amount of

15 from 0.1 to 10 wt. percent based on the weight of the hydrocarbon.

6. A process according to claim 1 wherein the promoter is dispersed on a support material and the hydrocarbon is contacted with the extractant by admixing the hydrocarbon and the elemental sulfur and passing the resultant mixture over the supported Group VB metal salt at a space velocity of from 0.01 to 100 v/v/hr.

7. A process according to claim 6 wherein the space 25 velocity is within the range of 1 to 5 v/v/hr.

8. A process according to claim 1 wherein the extractant is separated from the hydrocarbon by allowing the extractant to settle from the hydrocarbon.

9. A process according to claim 1 wherein the extractant is separated from the hydrocarbon by dissolving the oil therefrom with a paraffinic hydrocarbon.

10. A process according to claim 1 wherein the promoter comprises a vanadium sulfide.

11. A process according to claim 10 wherein the promoter comprises a mixture of a vanadium sulfide and vanadium oxide.

12. A process according to claim 10 wherein the promoter is vanadium sesquesulfide, vanadium pentasulfide or a mixture thereof.

13. A process for reducing the level of metal contaminants in a hydrocarbon material selected from the group consisting of crude oil or a residual petroleum fraction containing the same which comprises contacting the hydrocarbon material at a temperature varying from 150° to 350°C. with an extractant comprising 0.05 to 5.0 wt. percent, based on the weight of the hydrocarbon, of elemental sulfur and from 0.1 to 10 wt. percent, based on the weight of the hydrocarbon, of an unsupported sulfide of vanadium and thereafter separating at least a portion of the extractant and metal contaminants from said hydrocarbon.

14. A process of claim 13 wherein said extractant comprises from 0.9 to 1.5 wt. percent, based on the weight of the hydrocarbon, of elemental sulfur and 0.5 to 2.0 wt. percent of an unsupported sulfide of vanadium.

15. The process of claim 13 wherein the extractant is separated from the hydrocarbon material by dissolving the hydrocarbon material with a paraffinic hydrocarbon.

16. The process of claim 14 wherein the extractant is separated from the hydrocarbon material by dissolving the hydrocarbon material with a paraffinic hydrocarbon.

17. A process for reducing the level of metal contaminants in a hydrocarbon material selected from the

group consisting of crude oil or a residual petroleum fraction which comprises contacting the hydrocarbon material at a temperature below 400°C. with an extractant comprising 0.001 to 10 wt. percent, based on the weight of the hydrocarbon, of elemental sulfur and an effective promoting amount of a promoter selected from the group consisting of the oxides, sulfides, and selenides of vanadium, tantalum, niobium or mixtures thereof, and thereafter separating at least a portion of the extractant and metal contaminants from said hydrocarbon material, the promoter being present in an

amount of from about 0.1 to 10 wt. percent, based on the weight of the hydrocarbon.

18. The process of claim 17 wherein the promoter is selected from the group consisting of vanadium sulfide, vanadium sesquesulfide, vanadium pentasulfide and mixtures thereof.

19. The process of claim 18 wherein the temperature ranges from about 150° to 350°C.

20. The process of claim 19 wherein the sulfur is present in an amount of from 0.5 to 5.0 wt. percent, based on the weight of the hydrocarbon.
